US00D804708S

(12) **United States Design Patent** (10) **Patent No.:** **US D804,708 S**
(45) **Date of Patent:** **** Dec. 5, 2017**

(54) **LIGHT FIXTURE**

- (71) Applicant: **IP Holdings, LLC**, Vancouver, WA (US)
(72) Inventor: **Christopher Reynolds**, Vancouver, WA (US)
(73) Assignee: **IP Holding, LLC**, Vancouver, WA (US)
(**) Term: **15 Years**
(21) Appl. No.: **29/596,630**
(22) Filed: **Mar. 9, 2017**

Related U.S. Application Data

- (63) Continuation of application No. 29/577,324, filed on Sep. 12, 2016, now Pat. No. Des. 786,488, which is (Continued)
(51) **LOC (10) Cl.** **29-99**
(52) **U.S. Cl.** **D26/118**

(74) *Attorney, Agent, or Firm* — J. Douglas Wells

(57) **CLAIM**

The ornamental design for a light fixture, as shown and described.

DESCRIPTION

FIG. 1 is a perspective view of a light fixture, as viewed from below, showing my new design;
FIG. 2 is a perspective view of the light fixture shown in FIG. 1, as viewed from above;
FIG. 3 is a left side view of the light fixture shown in FIG. 1;
FIG. 4 is a right side view of the light fixture shown in FIG. 1;
FIG. 5 is a front elevation view of the light fixture shown in FIG. 1;
FIG. 6 is a rear elevation view of the light fixture shown in FIG. 1;
FIG. 7 is a top plan view of the light fixture shown in FIG. 1; and,
FIG. 8 is a bottom plan view of the light fixture shown in FIG. 1.
The broken-line disclosure shown in the views is understood to represent portions of the article in which the claimed design is embodied, but which form no part of the claimed design.

1 Claim, 6 Drawing Sheets

US D804,708 S

Page 2

Related U.S. Application Data

a continuation of application No. 29/524,011, filed on Apr. 15, 2015, now Pat. No. Des. 769,513.
